COKE OVEN BY-PRODUCTS RECOVERY APPARATUS

Joseph Wallace Allen, Clairton, and Hobart William Seyler, Elizabeth, Pa., assignors to Koppers Company, a corporation of Delaware

Application May 25, 1935, Serial No. 23,512

2 Claims. (Cl. 23—263)

This invention relates to the recovery of coke-oven by-products and is primarily concerned with the removal of ammonia from weak ammonia liquor so that little or no phenol is driven off with the ammonia or left in the ammonia-free liquor.

Equipment is available which removes the ammonia liquor after it has passed the free leg of the ammonia still, contacts it with steam for the recovery of the phenol contained thereby and returns it to the lime leg of the still, the phenol being recovered in the form of sodium phenolate by treating the steam, which recovered it from the liquor, with caustic soda. This recovers some of the phenol but the phenol that escapes from the free leg of the still along with the ammonia vapors and/or acidic gases is a loss of sufficient amount to result in noticeable atmospheric pollution should it ultimately be released from the vapor system.

The acidic gases should be removed from the ammonia liquor before it goes to the phenol removal equipment to avoid the acidic gases liberating the phenol from the sodium phenolate formed in the phenol removal equipment and thus interfering with the efficient recovery of the phenol.

The primary object of the present invention is to retard or prevent the above mentioned escape of phenol and to thereby increase the amount of phenols recovered when such phenol recovery equipment is used in combination with an ammonia still. Other objects may be inferred from the following disclosure.

Having reference to the accompanying drawing, which illustrates equipment of the character under discussion in partially sectioned elevation:

Ammonia liquor is forced by a pump 1 through a pipe 2 and so into the free leg 3 of the ammonia still where the free ammonia and/or acidic gases are driven off, these leaving by a pipe 4 which carries them to an unillustrated gas system. The liquor, from which the acidic gases are now removed so as to avoid the liberation of phenol from the sodium phenolate in the phenol recovery equipment, is forced by a pump 5 through a pipe 6 to dispersers 6^a at the top of a chamber 7. As it falls through this chamber it is subjected to the action of steam which is continually recirculated by means of a blower 8 and conduit 9, this steam absorbing the phenols from the ammonia liquor and being subsequently subjected to caustic soda which is introduced to it through a pipe 10 and dispersers 10^a and which absorbs the phenol from the steam by forming

sodium phenolate. The liquor returns to the lime leg 11 of the still by way of a pipe 12, where it reacts with milk of lime and goes to the fixed leg 13 of the still through a connection 11^a. The phenol is subsequently sprung from this sodium phenolate with acid. The sodium phenolate does not remain in the liquor returned to the lime leg of the still but is removed from the chamber 7 by way of an outlet 7^a. The top of the fixed leg 13 interconnects with the bottom of the free leg through a connection 13^a so that steam introduced by a pipe 14 to the bottom of the fixed leg also passes through the free leg. Obviously the steam driving off the ammonia from the fixed leg also drives off the free ammonia and/or acidic gases from the free leg. The ammonia-free liquor then leaves the fixed leg through a pipe 15.

The above is described briefly because it is prior art. As previously noted, it does not prevent objectionable amounts of phenol escaping from the free leg along with the ammonia vapors and/or acidic gases which are leaving through the pipe 4 and are on their way to the gas system.

After careful study the present inventors discovered that considerably more steam is required to effect the proper driving off of the ammonia in the fixed leg than is necessary to remove the ammonia and/or acidic gases from the liquor in its passage through the free leg. Furthermore, that when sufficient steam is supplied the fixed leg it discharges so much steam to the free leg that considerable phenol is driven off with the ammonia and/or acidic gases. These inventors then tried reducing the steam passed through the free leg by utilization of only that portion of the steam from the fixed leg which is required for the removal of sufficient amounts of the acidic gases to permit efficient recovery of the phenol by the phenol recovery equipment and, at the same time, passing sufficient steam through the fixed leg to also meet the requirements of the latter. The results proved to be excellent, the phenol formerly escaping with the ammonia vapors and/or acidic gases from the free leg being reduced to a satisfactory minimum and, furthermore, being retained in the ammonia liquor which is passed to the phenol removing equipment whereby it can be efficiently recovered as sodium phenolate.

The equipment illustrated by the drawing includes one example of a practical embodiment of the above discovery. Thus, it is to be noted that a pipe 16 by-passes steam from the fixed leg 13 around the free leg 3 and into the pipe 4. A thermostatically controlled valve 17 is inserted

into this pipe with its operating thermal-element inserted into the top of the free leg and connected to it by a line 18. This valve may be set to automatically by-pass enough steam to limit the steam discharged from the fixed still, through the connection 13^a, to the aforesaid requirements of the free leg, this being done independently of the requirements of the fixed leg.

This improvement makes the phenol-removal equipment completely successful in accomplishing its intended purpose.

It is obvious that the valve 17 can be operated by the pressure in the free leg, or to proportionately divide the steam from the fixed leg. Also, a manually operable valve can be used if automatic operation is not desired.

The usual way of determining the loss of phenol by way of the vapors leaving the free leg is to shut off the phenol recovery apparatus, analyze the liquor leaving the still and then operate the phenol recovery apparatus and determine the percentage of phenol actually recovered. It is obvious that those skilled in the art can easily regulate the valve 17 so as to reduce the phenol loss to a minimum or, to put it another way, to adjust the valve so as to recover the greatest possible percentage of phenol by the phenol recovery apparatus.

It follows from the above that the invention

is not to be limited to the specific example shown by the drawing but only by the scope of the following claims.

We claim:

5 1. Coke-oven by-products recovery equipment including the combination of an ammonia still having a free leg, a lime leg and a fixed leg which discharges steam passed therethrough into said free leg, means for removing phenol from ammonia liquor after it has left said free leg and before it enters said lime leg, and means responsive to vapor conditions in said free leg for varying the amount of steam discharged from said fixed leg into said free leg.

10 2. Coke-oven by-products recovery equipment including the combination of an ammonia still having a free leg, a lime leg and a fixed leg which discharges steam passed therethrough into said free leg, means for removing phenol from ammonia liquor after it has left said free leg and before it enters said lime leg, and means responsive to vapor conditions in said free leg for by-passing steam discharged from said fixed leg around said free leg whereby the steam passed through the latter is limited to a determinable amount.
